UNITED STATES PATENT OFFICE.

WILLIAM J. TRETCH, OF PHILADELPHIA, PENNSYLVANIA, ASSIGNOR TO
FREDERICK A. RIEHLÉ, OF PHILADELPHIA, PENNSYLVANIA.

GRIP FOR TESTING-MACHINES.

SPECIFICATION forming part of Letters Patent No. 759,646, dated May 10, 1904.

Application filed December 17, 1903. Serial No. 185,478. (No model.)

To all whom it may concern:

Be it known that I, WILLIAM J. TRETCH, a citizen of the United States, residing in the city and county of Philadelphia, State of Pennsylvania, have invented a new and useful Improvement in Grips for Testing-Machines, of which the following is a specification.

My invention consists of a grip for testing-machines. It particularly applies to testing-machines in which the tensility of a piece of cement or other substance is to be ascertained. It provides against a spreading or springing open of the ends of the grip.

It further consists of novel features of construction, all as will be hereinafter fully set forth.

Figure 1 of the drawings represents in front elevation a grip embodying my invention. Fig. 2 is a vertical section through line $\alpha\alpha$, Fig. 1.

Similar numerals of reference indicate corresponding parts in the figures.

Referring to the drawings, 1 designates the body of a grip having jaws 2 2 adapted to engage the test specimen. The cross-bar 3, bolted to the body 1, is provided with a center point 4, adapted to engage with the stirrup or hook through which strain is applied.

At the end of each of the jaws 2 is a roller 5, mounted on a pin 6. A solid back 7, shown as integral with the body 1, connects the jaws 2 2 and may be provided with a boss 8, against which the test specimen may bear. It will be seen that the solid back 7 acts to firmly hold the jaws 2 2, so that they cannot be spread apart by any strain that can be put upon them. In the earlier forms of the device—such, for instance, as that shown in United States Patent No. 657,566, granted to F. A. Riehlé September 11, 1900—the slight spreading of the jaws which occurs when considerable strains are applied to break the test-piece has seriously interfered with the exactness of measurement.

My invention supplies a reinforcing portion, connecting the jaws beyond their juncture

with the body, by which the tendency to spread apart is entirely obviated.

It will of course be understood that the rollers 5 form no part of the present invention; that these may, if desired, be covered with soft or pliable material, as shown in the patent above alluded to, or they may be dispensed with entirely, as in some earlier forms of grips. It is also clear that the method of hanging the grip or grips, as two of these are of course required in each testing-machine, is immaterial to my invention—that is, any other form of connection with the stirrup or clevis may be substituted for the center point 4 shown. It is also plain that other changes may be made in my device without departing from the spirit of my invention—e. g., the body 1 and cross-bar 3 may of course be integral.

The particular feature of my device is the “solid-back” grip in which the jaws between which the test specimen engages are connected by an integral back or reinforcement.

Having thus described my invention, what I claim as new, and desire to secure by Letters Patent, is—

1. In a grip for testing-machines, a body, a pair of jaws and a reinforcing portion connecting said jaws beyond their juncture with said body, said body, jaws and reinforcing portion being integral.

2. In a grip for testing-machines, a body, a pair of jaws and a solid back integral with and connecting said jaws.

3. A grip for testing-machines comprising an integral body, jaws and reinforcing portions connecting said jaws beyond their juncture with said body, a cross-piece above said body and forming therewith a recess, and a center point secured to said cross-piece and located in said recess.

WILLIAM J. TRETCH.
